UNITED STATES PATENT OFFICE.

JAMES E. O'NEILL, OF WAUPACA, WISCONSIN.

HEEL.

SPECIFICATION forming part of Letters Patent No. 606,229, dated June 28, 1898.

Application filed December 27, 1897. Serial No. 663,460. (No model.)

To all whom it may concern:

Be it known that I, JAMES E. O'NEILL, a citizen of the United States, and a resident of Waupaca, in the county of Waupaca and State 5 of Wisconsin, have invented certain new and useful Improvements in Heels; and I do hereby declare that the following is a full, clear, and exact description thereof.

My invention contemplates finished heels 10 provided with simple economical means for ready attachment to boot or shoe soles; and it consists in certain peculiarities of construction and combination of parts hereinafter set forth, with reference to the accompanying drawings, and subsequently claimed.

Figure 1 of the drawings represents a plan view of a heel provided with means for its ready permanent attachment to a boot or shoe sole, and Fig. 2 a transverse sectional view of 20 the heel connected to a sole.

Referring by letter to the drawings, A represents a heel made separate from a boot or shoe sole and properly finished, this heel being provided with a longitudinal central cavity 25 at the top. The cavity may be open, as herein shown, or, if found desirable in practice, the upper layer of the heel may be made to cover said cavity, this being a matter of structural detail that in no way affects the 30 scope of my invention.

The upper cavity in the heel is sufficiently wide to permit the play of a pair of clamp-slides B C, herein shown as being recurved metal plates that interlock in one position of 35 their adjustment and have outwardly-extended hook-arms b c, that move in corresponding guide-grooves with which said heel is provided. The hook ends of the plate-arms b c are for engagement with boot or shoe sole D, 40 and a hook-plate d, made fast to the central rear upper portion of the heel, also engages with said sole.

Near its forward end the bend of the clamp-slide C is shown provided with an aperture e 45 for the engagement of a spur f, projecting from a longitudinal edge of a lock-plate E, that is pushed into engagement with the recurved edges of said clamp-slides to lock the latter in their engagement with a boot or shoe sole.

Heels of the kind herein shown may be at-

tached to soles of boots or shoes by manufacturers of such goods to take the place of heels that are generally built on said soles, layer upon layer, pegged or nailed in place; but they are especially designed as substitutes for 55 the latter kind of heels after the same have become worn, or knock off, and the construction and arrangement of parts being such that the services of a shoemaker are not necessary in making the substitution.

To attach a heel such as I have shown and described, the clamp-slides are adjusted laterally as far as their interlocking recurved longitudinal inner edges will permit. The heel is then set in place so as to have its rear hook-plate d engage with the boot or shoe sole, after which said clamp-slides are pushed in to cause engagement of their hook-arms b c with said sole, and then the lock-plate E is forced into place to effectively maintain the union 65 of said heel and sole, there being permanent engagement of lock-plate spur f with the aperture e in the bend of one of the aforesaid clamp-slides.

The rear hook-plate d of the heel prevents 75 the latter from working forward on the boot or shoe sole, and lock-plate E is virtually a wedge that operates to spread the clamp-slides B C apart and cause draw of their hook-arms 80 on said sole.

Having thus described my invention, what I claim as new, and desire to secure by Letters Patent, is—

1. A heel having an upper cavity, a pair of clamp-slides consisting of recurved metal 85 plates having a lateral adjustment in the heel-cavity and provided with outwardly-extended hook-arms movable in corresponding guides in the heel, a wedging lock-plate engageable with the clamp-slides, and a hook-plate fast 90 to the rear upper portion of said heel, this hook-plate and hook-arms of said clamp-slides being for engagement with a boot or shoe sole.

2. A heel having an upper cavity, a pair of clamp-slides consisting of recurved metal 95 plates having lateral adjustment in the heel-cavity and provided with outwardly-extended hook-arms movable in corresponding guides in the heel, a wedging lock-plate engageable with the clamp-slides and provided with a lat- 100

eral spur that enters an aperture in the bend of one of said slides, and a hook-plate fast to the rear upper portion of said heel, this hook-plate and hook-arms of the aforesaid clamp-slides being for engagement with a boot or shoe sole.

In testimony that I claim the foregoing I

have hereunto set my hand, at Waupaca, in the county of Waupaca and State of Wisconsin, in the presence of two witnesses.

JAMES E. O'NEILL.
